APPARATUS FOR CONTINUOUS TREATMENT
OF YARNAlvin L. Ewing, Chester, Va., assignor to E. I.
du Pont de Nemours & Company, Wilmington,
Del., a corporation of Delaware

Application December 30, 1948, Serial No. 68,357

12 Claims. (Cl. 8—151.1)

1

This invention relates to the provision of apparatus for and method for continually spinning and processing yarn and the like. More particularly it relates to advancing and storing yarn and the like.

By the processes and apparatus of this invention shaped articles are advanced, stored and treated in a continuous fashion. By "shaped articles" is meant yarns, threads, monofil, ribbons, strands and the like. While the discussion below pertains in the main to the continuous spinning of viscose, it is understood that the apparatus described herein may be employed wherever a shaped article is to be advanced or stored.

It is well-known that yarn may be advanced in the form of a helix upon a variety of reels. These reels usually involve a considerable number of moving parts. A typical example is the reel in which yarn carrying bars move outward into contact with the yarn, then forward carrying the yarn in this movement, then inward out of contact with the yarn and finally backward to repeat position. Commercial use of advancing devices hitherto known, such as the illustrated reel, involves a large number of units and considerable maintenance cost. Reduction in both items is highly desirable.

An object of this invention is to provide a new advancing device and process. Another object of this invention is to provide an advancing device which involves simple construction and relatively few moving parts. A further object is the provision of an advancing device in which the article being advanced after contacting the device does not change its position relative to that of the device during advancement. A still further object is the provision of a new process for advancing, storing and winding shaped articles. Other and additional objects will appear hereinafter.

The objects of this invention are accomplished, in general, by winding the shaped article to be processed on a rotating, traveling cylinder, the cylinder being forwarded horizontally or vertically and preferably horizontally. The article is fed to the cylinder, and as the cylinder rotates and moves axially the article collects on the cylinder in the form of a helix which is carried forward. During this advancement the article is treated in one manner. The article is advanced a desired distance to a take-off point from which it passes to another rotating cylinder traveling in the same, or preferably, the opposite direction. Similar wind-up and advancement occur and the

2

next processing step is accomplished on this cylinder. The procedure is repeated until processing is completed. The final product is then wound in suitable packages. The cylinders may be in a tier or a horizontal arrangement.

The apparatus, then, comprises a cylinder which has rotary and rectilinear movement. As it rotates, it travels in a path parallel to its longitudinal axis of rotation. In order to keep the supply of cylinders constant at the various article-contacting areas, a plurality of these rotating traveling cylinders is used. A transfer means is employed for supplying the cylinders at a controlled rate to the article receiving areas and for removing the cylinders from these areas in a controlled manner. This transfer means comprises, for example, an endless driven conveyer having a plurality of cylinder carriers fixed thereto. In the tier arrangement, this conveyer is in the form of an elevator and the cylinder carriers are actuated by a trip mechanism to dump a cylinder at the cylinder receiving and forwarding unit near the receiving end of the article-contacting area or to receive a cylinder at the removal end of the area. In another arrangement involving horizontal transfer of cylinders, a slidably mounted, traversing arm having a cylinder carrier attached to one end and, if desired, running on a semi-circular horizontal track is used to transfer a cylinder from a removal end of one article-contacting area to the receiving end of another article-contacting area. The traversing arm is actuated by trip mechanisms and is driven by a reversible torque motor. The trip mechanisms are devised to be actuated by the absence of a cylinder or by the presence of a cylinder depending upon the location of the device. When a cylinder is received to be transported to the article-contacting area or when the cylinder has just been removed from an article-contacting area, it is moved by a forwarding unit either to or away from the main line of cylinders, respectively. Such a unit may be, for example, a plurality of driven rolls cooperating with a plurality of askewed rolls. This unit drives the cylinder at an accelerated rate so that it catches up to the main cylinder line or is removed from it rapidly. The cylinders are rotated and forwarded, for example, by passing them through a stationary casing having a rotatable inner ring which when rotating supports the cylinders, rotates them and moves them forward. This inner ring has mounted on it a plurality of driven rollers the axes of rotation of which are 90° to

the axis of the inner ring. These rollers which are driven move the cylinders forward through frictional contact with the cylinders. Similar supporting means may be placed at various places along the main cylinder line which is made up of a plurality of cylinders the ends of which are digitated so that adjacent cylinders are joined together. By this method of joining, the main cylinder line rotates and travels as a single unit.

The invention will be more fully understood by reference to the following detailed description and to the accompanying figures, in which like numbers designate like parts, and of which

Figure 1 is a sectional elevation taken through the various tiers of cylinders and at right angles to their paths of travel and showing the several floor levels and equipment associated with the process;

Figure 2 is a plan view (on a larger scale than Figure 1) of one flight of cylinders and adjacent spinning mechanism and further illustrating elevators located in line with, and at each end of the travel path of the cylinders;

Figure 3 is a sectional plan taken on line 3—3 of Figure 6 showing a cylinder being transferred from the elevator to position in line with its path of horizontal travel;

Figure 22 is a front elevation of the right hand end of Figure 21, and some of the cylinders as shown in Figure 19;

Figure 23 is an end elevation of Figure 22 and

Figure 24 is a sectional elevation taken on line 24—24 of Figure 21 and shows the trip device in more detail.

In Figure 1 the thread, indicated by the broken line 1, is formed in the spinning bath 2 which contains numerous spinning jets 3 or spinnerets so that a plurality of threads is formed. While the description which follows is made in reference to the treatment and path of a single end it is to be understood that each thread formed in the long spinning bath 2 is treated similarly to and follows a corresponding path to the reference thread. The plurality of threads and spinning jets can be seen more clearly in Figure 2 which is a plan view of the apparatus.

The thread 1 passes from the spinning bath up to the cylinder 4 which can be the acid cylinder. This cylinder is rotating in a clockwise direction and is moving at the same time horizontally, say to the right. As the cylinder rotates, any desirable number of wraps of thread 1 are taken in keeping with the space allowed by the number of spinnerets in use before the thread end is passed downward to the next cylinder 5 which may be the preliminary wash cylinder. Thus, it will be seen that the thread goes on the cylinder at one point and due to the rotation and horizontal movement of the cylinder 4 it is taken off at another point some distance from the point of feeding. This distance can be varied between wide limits. Usually the width of the band on the cylinders will be adjusted so that proper processing is obtained during the time the yarn is on the cylinder. In each instance the rates of rotation, cylinder travel, yarn feeding and removal and processing are synchronized. Thus, the yarn leaving acid cylinder 4 has been adequately coagulated and regenerated by the acid treatment. On cylinder 5 the yarn is given a preliminary wash. Like cylinder 4 this cylinder

is rotating in a clockwise direction but is moving in the opposite horizontal direction. The preliminary wash treatment may be any of the known washings designed to reduce or remove the acid used in coagulation. From cylinder 5 the yarn passes to cylinder 6 which may be for desulfuring. This cylinder rotates counter-clockwise and moves in the same direction as cylinder 4. Intermediate washing of the yarn may be done on cylinder 7 which again reverses the horizontal yarn direction and is rotating counter-clockwise. On cylinder 8, which rotates and moves like cylinder 4, the yarn may be given a bleach treatment. From 8 the yarn is passed to cylinder 9, rotating counter-clockwise and moving to the left. On this cylinder finish may be applied to the yarn. Preliminary drying is done on cylinder 10 rotating counter-clockwise and moving to the right. Final drying of the yarn 1 is done on cylinder 11 rotating clockwise as it moves to the left. The yarn 1 then passes to a take-up roller 12 then to a thread-guide 13, such as a pigtail guide, and finally to a wind-up package 14, such as bobbin cap twister.

The rotation and direction of movement of the respective cylinders as described above is not essential. The cylinders may rotate in the same direction or any arrangement of rotation desired may be used. A desirable arrangement is one which facilitates string-up of each cylinder; and

such an arrangement is one in which each cylinder is on a different floor level and a rotation sequence, as that described above, is adjusted so that each cylinder is rotating toward the operator on the particular floor level. Difference in rotation of the cylinders is readily accomplished in any convenient way. For example, the common vertical shaft drive 54 described below can be equipped with a right and left hand cut gear at the appropriate place where a change of direction is desired. The direction of horizontal movement again is not critical. However, in the interests of saving space, maintaining simple construction and synchronizing cylinder supply it is preferred to have each cylinder moving in a horizontal direction opposite to the preceding and subsequent cylinders. By so doing the cylinder area is used most efficiently, for the yarn can be made to come off the last cylinder at a point approximately under the starting point on the first cylinder.

Appropriate fume, ventilating, air ducts, etc. are provided for. For example, a large fume duct 15 is mounted at the top of the machine frame 16 which supports cylinders and certain other apparatus. Likewise, ventilation ducts 17 are provided at the various floor levels 18. Auxiliary fume ducts such as 19 may be supplied. A preliminary drying exhaust duct 20 may be provided for as well as a final dryer exhaust duct 21. The preliminary drying and the final drying may be accomplished, for example, with hot air supplied by the motor driven fan 22 driving air over steam coils 23. The warm air passes over the yarn and is removed via exhaust ducts 20 and 21. Any convenient and conventional drying means may be used. Under those cylinders on which liquids are applied during processing suitable drip catch pans 24 and drip trough returns 25 are placed. Appropriate supply and removal lines are used. Further, around the cylinders are enclosures which have removable fronts to facilitate string-up.

A suitable device for starting the thread around the cylinder comprises a spring clip of such size to permit it to extend a little more than half way around the cylinder. The end of the yarn is passed between the handle of the clip and is pulled tight in the thread holder. The clip is pushed onto the revolving cylinder and then revolves with the cylinder. After the desired number of turns is placed on the cylinder, the clip is caught by the operator or by an automatic stop release and the clip, still carrying the end, is placed on the next cylinder or the end is started on the wind-up device.

The spinning operation conducted at the top floor or the spinning floor level may be seen in Figure 2. The viscose or other material to be wet-spun is forced through a plurality of spinners 3 contained in the coagulating bath 2. This arrangement is not essential. The apparatus of this invention may be used to accommodate filaments prepared by dry-spinning techniques or the filaments may be taken from a plurality of supply packages. Figure 2 illustrates how each main cylinder line is composed of a plurality of cylinder sections. As shown, each yarn 1 is wrapped around main cylinder line 4 a number of times to form a wrap 26. Similar wraps appear on the succeeding main cylinder lines 5, 6, 7, 8, 9, 10 and 11 beneath cylinder 4. These wraps may vary in width, in the number of turns of yarn, in yarn spacing and in the distance between wraps. Generally, it is desirable

to have wraps which maintain a continuous film of processing liquid over the width of the wrap at every point.

In this connection it is possible to employ on each cylinder the continuous yarn carrying device described in my copending application Serial No. 778,918. This device comprises an endless belt which advances helically on the advancing device, such as a reel or the traveling cylinder of this invention. The belt is composed of an elastic or expandable material and it contacts all or a portion of the surface of the advancing device. The yarns are arranged side by side initially under high or low tension. The 10 yarns advance along the advancing device with the belt acting as a direct carrier. The belt surface supports a continuous film of the applied liquid so that during processing the filaments are at all times covered by a continuous film of liquid. 15 The filaments are held in their respective positions by virtue of their frictional contact with the belt. The belt may be used during drying steps in a similar manner. This modification permits the purification and drying of filaments 20 under low tension. Appreciable tension is avoided. Further, no effort need be taken to maintain a film by proper spacing of filaments. The film is continuous even though the yarn turns in the plurality or in the band 26 are relatively far apart. Still further, this modification eliminates 25 strain and wear on the yarn and leads to a substantial increase in yarn quality.

Shown in Figure 2 is a cylinder section 27 in elevator 28. This, like the other sections shown, 30 has at its ends fingers 29 permitting the coupling of it to another in an interdigitating fashion. This construction is shown more clearly in Figures 7, 8, 9, 10 and 11. Figures 7 and 9 show how the fingers are alternated so that the notch 35 or recess 30 at one end can receive a finger 29 of an adjacent cylinder while the finger 31 directly at the other end fits into a recess of still another adjacent cylinder. A number of cylinder sections are shown in Figure 2 making up the main cylinder line 52 (which is any main cylinder line 4, 5, 6 etc.)

While smooth cylinders may be employed it is preferred to use cylinders which are corrugated or have ridges or elevations 32 as shown in Figure 8, an end view of a cylinder. The yarn or filament rides on these ridges practically in point contact with them. This is preferred since an optimum penetration or washing by the treating liquid is obtained. Of course, if a belt is used as described above, there is no need for the corrugated cylinder. When a belt is not used, the ridged cylinder is preferred to the smooth cylinder for the greater efficiency in processing obtained.

Actually, in the preferred ridged cylinders, the ridges are slightly raised and lowered alternately near the junction to prevent the yarn from being caught in the separation between two sections. Figure 9 shows the slight elevation 33 in the ridge near the digit 31. This elevation runs over a small area as shown in Figure 9. This elevation 33 and the alternating feature can be seen also in Figure 10 which is taken on line 10-10 of Figure 7. The normal height of the ridge 32 having the elevation 33 is shown in Figure 11 taken on line 11-11 of Figure 7. The periphery around the cylinder across the area remains constant so that yarn tension will not be affected along the entire length of the cylinder.

The cylinders may be constructed of a large

variety of materials such as glass, enamelware, extruded aluminum, formed stainless steel tubes, plastic materials such as molded Bakelites, etc. The cylinder construction may be of any type which permits satisfactory advancement and processing of the filaments and the proper coupling, rotation and advancement of the cylinders.

As can be seen in Figure 2, the cylinder 21 is at the top of elevator 28 and is ready for coupling. That is, it is ready to be joined to the main cylinder line 52 which is composed of a plurality of cylinder sections like section 27. A transfer mechanism in the elevator moves the cylinders into the drive mechanism 34 or means for simultaneously rotating and advancing the cylinders. The cylinders may be washed and cleaned in mechanism 35 as shown in Figures 17 and 18. As the cylinders move forward they are supported by mechanism 53 as shown in Figure 14. They are passed to the spinning point where they receive and carry yarn wraps 26. After moving away from the yarn wraps 26 they are passed to elevator 28 at the opposite end. If desired, additional driving and washing mechanisms may be located also at the off-coming end.

The elevators 28 are more fully described by Figures 3, 4, 5 and 6. The latter, an end view, shows an endless conveyor 36 or chain riding on sprockets 37 driven by motor 60 through shaft 59. The conveyor may be driven independently of means 34 and may be driven continuously or intermittently. Attached to the conveyor and moving with it are a plurality of cylinder carriers 38. The number and the distance between cylinder carriers 38 and the speed of the endless conveyor belt 35 are synchronized so that a fresh cylinder is available at any point when needed and so that a cylinder ready for ejection and transfer is removed with dispatch, being picked up immediately upon separation from the main cylinder line.

To illustrate the removing and supplying of cylinders in more detail, reference is made to cylinder section 39 in Figure 6 which section is about to be ejected. When the cylinder 39 is removed from the main cylinder line and is to go into the elevator system, it is received on a set of rolls. Three of these rolls are driven rolls 42 and are driven at the same peripheral speed as that of the main cylinder. The remainder of the rolls, three in number also, are askewed rolls 43 and are free turning and are opposite to rolls 42. Figure 4 shows these rolls in a different view. The askewed rollers 43 are positioned nearer the bottom of the cylinder section than the driven rollers 42. This is done to get more frictional contact with the askewed rollers than with the driven rolls. Further, the askewed rollers have a swivel base so that they may be set at any desired angle. The askewed nature of the rolls allows for accelerating or retarding the rate of cylinder travel. These rolls 42 and 43, which may be more or less in number than indicated, cooperate to feed the cylinder section 39 away from the remaining main cylinder. Due to the askewed nature of rolls 43 the section 39 moves rapidly away from the remaining cylinder which is still carrying yarn. Thus, it actually is made to travel faster than the remaining main line of cylinders which is still carrying yarn. As shown in Figure 4, as cylinder 39 moves, it strikes a trip roller 44 which is tapered. In its accelerated movement on askewed rolls 43 and driven rolls 42, cylinder

39 passes the trip roller 44 and contacts a stop 103 which is a rotatable disk. The striking of the trip roller causes the electrical circuit (not shown) to the solenoid 108 to be closed. A plunger 104 is extended thereby and a rod 105, in slidable bearings in skids 106, is pushed to the left thereby compressing spring 107. This positions lever arm 41 in line with the roller lug 40 on the conveyor chain (see Figure 6). As the chain moves downward the lug 40 pushes lever arm 41 downward, this arm being pivoted at point 46. The shaft or rod 105 is rotated and arms 45 are made to rise and push cylinder section 39 off the rollers and it rolls by gravity down skids 47 into the carrier 50 which is descending. In event this carrier has a section already in it, a trip mechanism (not shown) prevents lever 41 from being actuated by lug 40. This mechanism may be operated by any convenient means and is generally actuated by the weight of the cylinder section in the carrier. The movement of the section 39 is shown in Figure 6 by the dotted lines 48 and 49.

As this cylinder section 39 continues around the elevator it at some time, as it travels upward, arrives at a level at which a new section is needed. As the main cylinder feeds away from the elevator, a trip roller drops when the cylinder end passes. A solenoid or similar means is actuated and the carrier 38 is caused to dump a new section of cylinder onto rollers 42 and 43. These cooperate in this position to advance the cylinder section 39 at a faster axial rate than the main cylinder until the section seats with the end of the main cylinder prior to entering the drive unit. After this section feeds into the drive unit, it is fed automatically with the remaining cylinder body.

In Figure 3, the end of the main cylinder line 52 has advanced a slight distance to the beginning of drive unit 34 and the open end still has some distance to travel before entering the unit. Carrier 51 is coming up and is carrying a cylinder section 39 in it. As the end of main cylinder line 52 clears the pivoted trip roller 44, an electrical switch to solenoid 108 is closed and plunger 109 is extended into the path of the dumping slide 110 which is attached to and ascending with the conveyor and carrier 51. The slide is so positioned that it causes carrier 51 to dump the cylinder section 39 out of the carrier down the skids 47 onto the rollers 42 and 43. These rollers rotate the cylinder section and move it horizontally toward and at a faster rate than the slowly receding main cylinder line 52. The section 39 moves the trip roller 44 back to its original position thereby opening the circuit to solenoid 108. Plunger 109 is retracted and subsequent carriers pass without dumping. Roller 44 is positioned so that the time for section 39 to reach it is not greater than the time required for the next carrier to rise into dumping position. Section 39 reaches the end of main cylinder line 52 and perfect seating of the ends is accomplished quite some time before the new section or the section with which it has joined reaches the yarn contacting point. There is no interference with the advancement of the yarn. When the fingers of the section 39 and those of the nearest section of the main line are meshed, section 39 becomes a part of the main cylinder line 52 and is driven by means 34, shown in Figure 12, through washing mechanism 35, the supporting mechanism 53 to the exit side of the apparatus. The invention is not limited to the

method and means described for supplying and removing cylinder sections and any equivalent methods or means may be used. Further, any conventional well-known timing devices may be employed to regulate the speed of travel, and rate of supply and removal of cylinders.

In Figure 5 the relationship of the various drive means 34, washing means 35 and supporting means 53 at the various floor levels may be seen. This view also shows the relationship of these devices and the various main cylinder lines to the elevator device with its endless conveyor 36 and the cylinder carriers 38. This view also shows a means for synchronizing the movements of the conveyor 36 and the main cylinder drive 34. This is done by utilizing a common driving means. Vertical drive shaft 54 has a plurality of bevel gears 55 which mesh with gears 56 of driving means 34. The bevel gears 57 cooperate with gears 58 which are driven through a motor 60. This or similar means insures the proper timing of the conveyor with the machine.

The means for driving and rotating the cylinders is shown in Figures 12 and 13. The unit consists of a stationary outer casing 61 which has a race 62 containing ball bearings on which an inner ring 63 rides as it revolves. The casing 61 may consist of two halves held together by bolts 64. The ring 63 has gear teeth 65 cut into it around its circumference. These teeth mesh with the teeth of drive gear 56' retained in bearings integral to the casing. This gear rotates the ring. The gear 56' is driven by gear 55 on drive shaft 54, the gear 55 meshing with gear 56 affixed to the same shaft as is gear 56'. The outer casing also has an internal worm thread 66 cut in it concentric to the races. Mounted on the ring 63 and rotating with it are three rollers 67 which are mounted in bearings contained in the ring so that the axis of rotation of the rollers is 90° to the axis of the ring. The axle 68 of each roller carries a worm gear 69 which meshes with the internal worm thread 66 in casing 61. As the ring 63 revolves worm gear 69 turns and the rollers 67 are thereby caused to revolve. These rollers are so arranged that the cylinder section 39 is gripped between the rollers as shown in Figure 12, and is held concentric with the ring. The cylinder, which revolves with the ring, is forced to move axially by the frictional contact with the rollers 67. The cylinder may be plain faced or it may be ridged. As shown in Figure 12 the ridges 32 and the rollers 67 do not interfere with each other since the rollers do not run over the ridges. A more positive control of the axial motion may be had, if desired by using cylinders having rack teeth and rollers having gear teeth meshing with the rack teeth. Normally, the frictional contact described is satisfactory and is preferred for the simplicity of structure and economy it provides. The whole driving unit 34 may be supported by arms 70 rigidly secured on the frame 16.

In Figures 14, 15 and 16 a means 53 for supporting the cylinders is shown. A bracket 71 is appropriately supported on or anchored to frame 16. The bracket 71 has three rollers 72 which support the ring 73 which is similar to the ring 63 contained in the drive unit 34. These rollers are mounted in any suitable manner on bracket 71. Rollers 72 are free running and revolve as ring 73 rotates. Inside ring 73 are three rollers 74 mounted at a 90° angle to the axis of the cylinder contained in the main cylinder line 52. Rollers 74 are mounted on axles 75 contained in

bearings 76 affixed to ring 73. The main cylinder line 52 is positively rotated and moved laterally by drive unit 34. As the cylinder line rotates it turns the ring 73. Ring 73 and the main cylinder line 52 rotate in the same direction and at the same speed. The rollers 74 permit the lateral movement of the cylinder line to continue unhindered. Figure 15, taken on line 15—15 of Figure 14, shows the relationship in a vertical view. This figure also shows a knife or guide 116 which is attached to one or more of the rollers 74 or 77. This knife is positioned, for example, below the yarn surface on the corrugations of the cylinder, so that if a thread breaks and continues to advance on the cylinder the wrap is cut by the knife, thereby avoiding advancing wraps.

A modification of the cylinder support is shown in Figure 16. The ring 73 and rollers 74 are dispensed with and three rollers 77 attached to bracket 78 are placed in direct contact with the main cylinder line 52. The three rollers 77 are in the positions shown of rollers 72 and 74 shown in Figure 14. The bracket 78, mounted on frame 16, is of appropriate smaller dimensions than bracket 71. The rollers 77 rotating on axles 79 in bearings 80 are mounted on a stud 81 so that one may lock the roller 77 at any given angle by means of lock nut 117. The rollers 77 are therefore angularly adjustable by mounting 81 so that the axis of rollers 77 can be made to be askewed to the cylinder axis. By this pivoted arrangement the axial movement of main cylinder line 52 may be retarded or accelerated. Retarding is frequently advantageous to insure proper seating between cylinder section and to prevent separation. This modification is simpler than that shown in Figures 14 and 15 and with the advantages described it is preferred for smooth, unridged cylinders. The support means described above are placed at regular intervals in a quantity sufficient to provide adequate support.

The mechanism 35, supported on frame 16, for washing and cleaning the cylinders during advancement is shown in Figures 17 and 18. The brushes 82, are positively driven by any suitable means, as, for example, by a motor driven belt operating on pulley 83 fixedly mounted on axles 84 the rotation of which rotates the brushes, which brushes may be rotated either in the same or in the opposite direction of the rotation of the cylinder line 52. These brushes contact the cylinders as they rotate and travel through the machine. Located near the brushes 82 are nozzles 85 through which water is forced. The jets of water are played on the cylinder. As shown in Figure 2 a washing chamber 35 can be located behind the drive unit 34 at the place of entrance of the cylinders and before the drive unit at the place of exit of the cylinders. Any arrangement and any number of washing chambers may be used. Wash water materials are appropriately collected, as in a drip pan and are conducted away for disposal or reclamation. By means of mechanisms 35 the continuous washing of the cylinders is achieved and clean yarn bearing surfaces are readily available and each cylinder section is completely cleaned on each cycle of axial advancement.

In Figures 19 to 24 is shown another form of the invention. The spinning solution is extruded through spinneret 86 in bath 87. The thread 1, travelling upward, is then wound on cylinder sections as indicated in Figure 20. Stretch is applied on the first cylinder on which the yarn is

wound and from there the yarn passes to succeeding cylinders for further regeneration, carbon disulfide removal, etc. The number of cylinder levels used depends on the treatments being applied to the particular thread. After leaving the last cylinder the yarn is sucked into the air stream in tube 88 into a waste bag 89. A gap 90 is located at the dryer level. When the process has been properly started the yarn is seized at the gap 90 and is carried by means of a vacuum string-up tool or a small constant torque motor string-up device to a dryer not shown. The dryer may be any of the conventional dryers known in the art. The drying apparatus disclosed in copending application of Conaway and Hitt Serial No. 720,030 filed January 3, 1947, issued as U. S. Patent No. 2,495,053 January 17, 1950, is particularly effective and desirable. The dryers referred to in that application can also be employed to advantage in the modification first described, that is, that shown in Figure 1 and related figures. By using the curved plate dryers, the height of the machine can be considerably reduced with resultant savings in space. The tube 88 may also be used as a dryer by inserting a high voltage resistance in the tube. From the dryer, the yarn passes to a spindle 91 driven by the winding machine 92. Suitable packages are thereby produced. As shown in Figure 19, washing means 35 and driving means 34 are located at the end of the machine. These and the transfer device used in this modification are more clearly shown in Figures 21, 22, 23 and 24.

In the transfer mechanism, which moves the cylinders in a horizontal plane, a central vertical spindle 93 is driven by a reversible torque motor 102. The top end of the spindle 93, held by bearing support 111, has a head 94 in which is a hole 95 at a 90° angle to the spindle axis. Through this hole extends an arm 96. This arm which is slidably mounted in hole 95 is attached to a transfer carrier 97 which may ride, if desired, on a semi-circular, horizontal track 98 with a straight run 99 extending on either side, as shown in plan Figure 21. If desired, a support 112 may be used for the track 98. The cylinder section runs into the transfer mechanism on askew rollers 100. These cause the section to be advanced faster and the section is separated from the main cylinder line 52. At a centered position the cylinder strikes a trip 101 which cooperates with switch 113 through arm 114 and spring 115. The motor 102 is actuated thereby through microswitch 113 and the spindle rotates and the arm 96 carries the transfer device 97 in which the cylinder section is contained around the track to the entering position, shown by dotted lines in Figure 21. There the cylinder section rides on the askew rollers 100 so that the cage 97 in effect backs off the cylinder section as it feeds into the drive unit 34. The cage 97 continues to be urged forward while the cylinder section joins the main line 52, the notches of the cylinder section becoming securely engaged with those of the main line. When the end of this section has been sufficiently advanced by the drive unit 34 the last cylinder section on the opposite end has advanced to the trip roller 101 on that side and actuates it so that the transfer drive motor 102 is reversed and the cage 97 is returned to receiving position. Simultaneously the cylinder section part ejected is picked up by the cage 97 on the left hand end of the machine and is moved to be fed at the receiving point on the left hand end, shown by dotted lines

in Figure 21. The cycle is thus completed and is ready for repeat. Timing is maintained and insured by any of the conventional timing devices. In any event, one set of cylinder sections cannot gain or lose on lateral advancement over the other set.

The apparatus and methods of this invention are advantageous in that there is a minimum of movement of the shaped article while it is advancing. Further, by simple adjustment, a main cylinder line may be made to rotate faster or slower than any adjacent line. Various speeds may be accomplished, for example, through the use of different gear ratios, or, if desired, each main cylinder line may be independently driven at a specified speed. By this means a shaped article, such as a yarn may be brought to the first cylinder under a certain tension and that tension may be reduced or increased at each subsequent cylinder as desired. In this manner it is possible to wash the yarn under a fairly high tension and then lower the tension at the desulfuring cylinder to allow for shrinkage. During further processing the tension is increased or decreased depending upon the type of yarn being processed. For high tenacity tire cord, the yarn may be held at uniformly high tension through all stages of processing. For textile yarns, the tension may be reduced to a point approximating complete relaxation through all the stages. In addition to cold stretching or drawing, it is also possible to heat the cylinders by any convenient means. Drawing in a continuous process is thus possible. For example, nylon yarns may be passed to a hot cylinder and then to a faster running cold cylinder and drawn thereby in a continuous fashion.

By the apparatus and processes of this invention, yarns and the like of any material may be continually advanced and stored and processed during advancing and storing. Such materials include natural materials such as cotton as well as synthetic materials, such as viscose, polyamides, polyacrylonitriles and the like.

Any departure from the procedure described herein which conforms to the principles of the invention is intended to be included within the scope of the claims below.

I claim:

1. In apparatus for advancing and processing yarn and like continuous structures, a supporting frame, a plurality of cylinder sections of substantially uniform diameter supported thereby in axial alignment, said sections being provided with means for coupling the sections in axial juxtaposition to form a cylinder unit, means for supporting said unit in said frame so as to be rotatable and longitudinally displaceable and means for rotating and advancing the coupled unit through a yarn-bearing zone in one direction only.

2. In apparatus for advancing and processing yarn and like continuous structures, a supporting frame, a plurality of cylinder sections supported for rotational and longitudinal movement in axial alignment in said frame, said sections being provided with means for coupling the sections in axial juxtaposition to form a cylinder unit, means for rotating and longitudinally advancing said unit with a screw-like motion, yarn feeding means for supplying yarn to said unit from a fixed position in said frame to wind a helix on the unit, means for coupling additional sections onto said unit as needed to maintain a continuous cylinder unit passing said feed-

13

ing means, means for withdrawing the yarn from said unit at a fixed point in said frame to maintain a fixed length of helix on said unit, and means for uncoupling from said unit sections from which yarn has been unwound and forwarding these sections for reuse.

3. In an apparatus for advancing and processing yarn and like continuous structures on a cylinder a plurality of cylinder sections coupled in axial juxtaposition to form a cylinder, means for supporting said cylinder so as to be rotatable and axially displaceable comprising a supporting frame, a rotatable ring supported thereby coaxially with said cylinder, and rollers supporting said cylinder mounted in said ring with the axis of rotation of each roller perpendicular to a plane which includes the axis of the ring and means for rotating and advancing the coupled cylinder sections through a yarn-bearing zone in one direction only.

4. Apparatus as defined in claim 3 in which said rollers are provided with driving means for rotating the rollers to displace said cylinder in an axial direction.

5. Apparatus as defined in claim 3 in which said ring is provided with driving means for rotating the ring to rotate said cylinder.

6. Apparatus as defined in claim 3 in which said rollers are rotated through worm and worm wheel gearing by rotation of said ring.

7. Apparatus for simultaneously rotating and axially displacing a cylinder so that a reference point thereon will describe a helix which comprises a stationary supporting casing having an internal worm thread, a ring revolvably supported within said casing means for revolving the ring in a single direction, a plurality of rollers mounted in said ring in position to support said cylinder with the axis of rotation of each roller perpendicular to a plane which includes the axis of revolution of the ring, and each roller being mounted on an axle on one end of which is a worm gear meshing with said internal worm thread of said casing to produce rotation of the rollers when said ring is revolved.

8. In an apparatus for advancing and processing yarn and like continuous structures in which the structure is wound as a helix on a cylinder for treatment and unwound from the cylinder after treatment, means for providing the equivalent of an endless cylinder which comprises a plurality of cylinder sections of substantially uniform diameter having digitated ends adapted to mesh

14

with one another in axial relationship for coupling sections to extend the cylinder preparatory to receiving the yarn for treatment and adapted for ready uncoupling after the structure has been unwound from the cylinder and means for rotating and advancing the coupled cylinder sections through the yarn treatment zone in one direction only.

9. Apparatus as defined in claim 8 in which said cylinder sections are provided with longitudinal ridges adapted to support the yarn and facilitate treatment.

10. Apparatus as defined in claim 9 in which said longitudinal ridges vary in height adjacent to the ends of the sections to help prevent yarn being caught between coupled sections.

11. Apparatus as defined in claim 8 which includes means for uncoupling sections from one end of said cylinder, means for conveying said sections to the opposite end of the cylinder and means for coupling said sections to the latter end of the cylinder.

12. A process for advancing and processing yarn and like continuous structures which comprises continuously winding yarn on a rotating, sectionalized cylinder which is simultaneously moved longitudinally in one direction only to form a yarn helix, treating the yarn while on the moving cylinder, continuously unwinding the helix after the yarn has been treated, and removing sections of the moving cylinder from which the yarn has been unwound and placing them on the opposite end of the cylinder in position to receive windings of untreated yarn.
